UNITED STATES PATENT OFFICE.

FRANZ WÄCHTLER, OF GROSSENHAIN, GERMANY.

CONTROLLING MECHANISM FOR WEFT-REPLENISHING LOOMS.

No. 908,362.

Specification of Letters Patent.

Patented Dec. 29, 1908.

Application filed July 9, 1907. Serial No. 382,880.

To all whom it may concern:

Be it known that I, FRANZ WÄCHTLER, a subject of the King of England, residing at Grossenhain, Saxony, Germany, have invented certain new and useful Improvements in Controlling Mechanism for Weft-Replenishing Looms, of which the following is a specification.

Devices for automatically replacing the consumed weft material of weaving looms are already well known, and there are in existence exchanging devices in which the whole shuttle is exchanged and exchanging devices in which only the weft spool is ex- 15 changed.

The present invention relates to improvements in apparatus of the kind employed for throwing into action those devices whereby a fresh supply of weft is effected without 20 stopping the loom just before the weft which is in use at the time is exhausted, the actuation of the weft replenishing device being timed to take place by calculating the number of picks corresponding to the length of 25 the weft thread.

The apparatus for throwing into action weft replenishing devices according to this invention consists, in its preferred form, of a gear with a disk slowly turned forward or 30 advanced by toothed wheel gear, which disk, by disengaging or throwing into gear a lever, renders the exchanging device operative in a given position. According to this invention the pick counter is capable of being doubly advanced on the one hand, directly by the loom drive and on the other hand by the gear which comes into operation only during the exchanging operation, for the reason that one of the sides of the 35 notch should be of appreciable length to insure satisfactory operation and the single advance of the loom drive would not bring the said notch sufficiently quickly out of reach of the lever projection to prevent a 40 second engagement of the lever and a second operation of the exchanging device.

A constructional form of device according to this invention as applied to a weaving loom with one shuttle is illustrated by way 45 of example in the accompanying drawings.

Figure 1 is a front elevation of the loom, Fig. 2 a corresponding side elevation, Figs. 3 and 4 show the gear for throwing into action the automatic shuttle exchanging device, Figs. 5 and 6 illustrate the mechanism which operates, when thrown into action by 50 the gear shown in the preceding figures, to move the levers effecting the change of shuttle, Figs. 7 and 8 show the cams for operating the said levers. Figs. 9 and 10 55 are sectional views of the batten in its relation to the shuttle magazine. Figs. 11 and 12 illustrate details of the shuttle box.

The driving shaft 1 is connected by means of a toothed wheel gear to the spindle 2, the 60 ratio of transmission being two to one. On the spindle 2 is mounted an eccentric 3 connected to an upwardly directed rod 4. The said rod is used for operating the gear which 65 throws into action the shuttle exchanging 70 device.

In Figs. 3 and 4 the gear which is mounted on a bed plate 5 secured to the frame of the loom, is shown in elevation and in horizontal cross-section. The rod 4 engages with a bell 75 crank lever 6 rotatable on a spindle 7 and carrying at the other end a pawl 8. The pawl engages with a ratchet wheel 9 in such a manner that at each revolution of the spindle 2, that is to say, at each descent of the eccentric rod 4, there is an advance movement. With the ratchet wheel rotates the spindle 7 mounted in two brackets 10 and 11 and provided with a toothed wheel 12 which is keyed 80 to its rear end. The said wheel 12 transmits the movement by means of the toothed wheel 13 to the spindle 14 arranged parallel to the spindle 7 and supported in brackets 15 and 16. At the front end the spindle 14 is provided with a disk 17 provided with 85 notches at the edge. The lever 18 is rotatable about a bolt or pin 19 mounted in the frame. Near the end of the lever is provided a projection 21 which rests on the disk 90 and is always pressed against the said disk by means of a spring 20 which is secured, on the one hand, to the bed plate 5 and on the other hand to the end of the lever. The other end of the lever is connected to a rod 22 which 95 throws into gear the automatic shuttle exchanging device. By suitably choosing the ratio of transmission and properly setting the notched disk, it will be easy to cause the lever 18 to oscillate after a given number of revolutions or of strokes of the batten. The 100 oscillation of the lever 18 will take place when the projection 21 drops into the notch in the disk 17. As the oscillations of the batten agree with the number of the picks 105 the operation of the exchanging device for the shuttles or the spool is rendered dependent on the length of the thread consumed.

Figure 1 is a front elevation of the loom, Fig. 2 a corresponding side elevation, Figs. 3 and 4 show the gear for throwing into action the automatic shuttle exchanging device, Figs. 5 and 6 illustrate the mechanism which operates, when thrown into action by 110

Although the length of thread on the weft spools and cops is mostly the same for yarn of the same number the length of thread can be if desired exactly regulated by a counting device at the spool machine. The gear for throwing into action automatic shuttle or spool exchanging device can be used for any spool or shuttle exchanging devices of well known kind. In the construction illustrated it acts on an automatic shuttle exchanging device, shown in detail in Figs. 7-12.

On the driving shaft 1 (Figs. 1 and 2, 5 and 6), the toothed wheel 23 is arranged so that it is longitudinally adjustable but rotates with the said shaft. A spring 24 is continually pressing it against the frame standard 25, so that the sleeve mounted on the toothed wheel rests with its end against a boss of the standard 25. The end of the sleeve of the toothed wheel 23 is of such shape as to form a face cam 26. When a pin 27 at a right angle to the axis of the spindle is brought into the path of the face cam 26 and the toothed wheel 23 rotates, a longitudinal movement will take place, the spring 24 being compressed, to such an extent that the toothed wheel 23 will engage with the toothed wheel 28 situated below it and mounted on the shaft 29 (Figs. 1 and 2). On the toothed wheel 28 is also mounted a disk 28^a provided with a recess. As soon as the toothed wheel 23 is moved out of reach of the recess, the disk 28^a can rotate to a sufficient extent, and the edge 28^b of the toothed wheel 23 can come to rest against the disk 28^a.

During the engagement of the toothed wheel 23 with the toothed wheel 28, the exchange of shuttles takes place. To the shaft of the toothed wheel 28 is connected a cam disk 29^a (Fig. 7). In the cam groove of the said disk travels a roller 30 (Fig. 2) secured to the end of a bell crank lever 31. To the other end of the bell crank lever is connected a rod 32 which effects the raising and lowering of the shuttle box 33. To the weaving loom frame is secured a magazine for receiving shuttles 34 which must be led into the shuttle box one after another. The magazine consists of two uprights of channel section 35 and 36 surrounding the shuttle points and connected by means of transverse bars 37 and 38.

The magazine is closed at the base by means of a plate 39 forming a portion of an angle part arranged at the end of a bell crank lever 40 (Fig. 2). The bell crank lever which is mounted at 41 on a frame pin, is provided at the other end with a roller 42 engaging with the cam groove of a second cam 43 (Fig. 8). The cam disk 43 is also mounted on the spindle of the toothed wheel 28. As soon as the pin 27 has been lowered into the path of the face cam 26, and the toothed wheel 23 connected to the toothed wheel 28, the following movement takes

place. First, the bell crank lever 40 is moved back in such manner that the plate 39 is moved out of reach of the magazine. The contents of the magazine can therefore fall downwards to the extent of the thickness of 70 a shuttle. The bottom shuttle then comes to rest on the shuttle box wall 44.

In normal working, the bottom box cell of the shuttle box is level with the path of the batten (Fig. 2). During the advance movement of the bell crank lever 40 which now takes place, the angle part secured to its end, drives the bottom shuttle into the upper box cell of the shuttle box. After the beating up of the weft the shuttle box is lowered (Fig. 80 10). Through two slots 46 and 45 in the back shuttle box wall 33 (Fig. 11) project two gripper-arms 47 and 48 (Figs. 1, 9 and 10) connected to a trough 49 situated at the bottom. At the second oscillation of the 85 batten, the shuttle situated in the bottom cell, owing to the descent of the shuttle box effected by the rod 32 mounted on the bell crank lever 31 comes within reach of the grippers 47 and 48. The bottom shuttle is, 90 therefore held fast during the oscillation of the batten and then slides into the trough 49 from which it is removed. The newly introduced shuttle passes through the shed to the other side of the loom, and while it is 95 there, the shuttle box returns to its normal position (Fig. 2). The swells 63 and 64 (Figs 11 and 12) mounted on the shuttle box or on its front edge and controlled by springs, are extended backwards beyond their center 100 of rotation and arranged in such manner that at the exchange of the shuttle they come into position shown in dotted lines in the drawing since the right hand end of the swell 63 is first pressed by a pin secured to the 105 shuttle box guide and secondly an arm 67 connected to the bell crank lever 40 presses against the end 65 of the swell 64 at the advance of the bell crank lever. In that way space is provided for the incoming 110 shuttle.

In order to remove the pin 27 from the face cam 26 again, the following provision has been made. A rod 50 (Fig. 2) surrounding with its bifurcated end the spindle 115 of the toothed wheel 28, is connected at the other end to a bell crank lever 51 which is pivoted at 52 on a frame pin. The rod 50 is provided with a pin having a roller 53 engaging with a groove of a cam disk which is also 120 mounted on the spindle of the toothed wheel 28. In that way the bell crank lever 51 is controlled. By means of a rod 54 connected to its other end, and engaging with its bifurcated end with a second bell crank lever 55, 125 the said lever 51 acts on the latter in such manner that the pin 27 surrounded by the other end of the bell crank lever 55, is raised or lowered. In order to maintain the pin in the normal, that is to say, in the raised pos- 130

tion, there is connected to the bell crank lever 55 a bar 56 provided with a downward projection 57. This projection, as soon as the pin 27 is raised, engages behind a tappet 58 or projection 58 secured to the frame bolt 52 of the bell crank lever 51. As soon, therefore, as the bar in question is lifted from the projection or tappet 58, the pin 27 is again lowered under spring action and the change 10 of shuttle begins. The rod 50 after the exchange of the shuttle has been completed raises the pin 27 or brings the projection 57 again into engagement with the projection 58 by means of the cam disk 52 and the roller 53. In this way the exchange of shuttles is started by the removal of the arm 56 from the tappet 58. The removal is effected by means of a rod 22 which on the one hand surrounds a pin on the bar and is 20 secured on the other hand to the lever 18 sliding on the notch disk of the gear.

A regular continuous advance of the gear is effected from the driving spindle or the spindle 32 by means of the rod 4, so that, for 25 instance, at each one-hundredth stroke of the batten, the lever 18 can be caused to move, that is to say, the shuttle exchanged. In order to insure that the oscillation of the lever 18 should take place after the 98th 30 pick, a rod 60 is coupled by means of a driver to the spindle 29 of the toothed wheel 28 (Figs. 1 and 2) which is rotated only during the exchange of shuttles, the said rod 60 being connected or pivoted to a bell crank 35 lever 61 rotatably mounted on the spindle 14 of the gear. The bell crank lever is provided at its other end with a ratchet pawl 62 engaging with the teeth of a ratchet wheel 63 connected to the notched disk 17. During 40 the exchange of shuttles, the ratchet pawl 62 effects an advance to the extent of

two teeth. Of course provision is made for effecting the advance only while the ratchet pawl 8 is out of engagement with the ratchet wheel 9.

45

What I claim as my invention and desire to secure by Letters Patent is:—

1. In a weft replenishing loom, a shuttle exchanging device, ratchet gear advanced from the loom drive, a disk advanced by 50 said ratchet, another disk operated by the first disk, a notch in said last-mentioned disk, a lever operated by said notch, a projection upon said lever, a second pawl, and means connected with the exchanging device 55 for moving said second pawl, whereby said notch is brought out of reach of said projection, for the purpose specified.

2. In a weft replenishing loom, a shuttle exchanging device, a rod, means upon the 60 loom shaft for reciprocating said rod, a pawl connected to said rod, a ratchet disk advanced by said pawl, gearing rotated thereby, another disk advanced by said gearing, a notch in said last-mentioned disk, a piv- 65 oted lever, a projection thereon and adapted to enter said notch, a spring on said lever, a rod connected to said lever at its end opposite said spring, means attached to said rod for operating the gear of the shuttle ex- 70 changing device, a second pawl, and means connected with said gear for operating said second pawl, whereby said notch is brought out of reach of said projection.

In testimony whereof I have signed my 75 name to this specification in the presence of two subscribing witnesses.

FRANZ WÄCHTLER.
